UNITED STATES PATENT OFFICE

ERWIN EICHENBERGER, OF DETROIT, MICHIGAN

INFORMATION-DISPLAY MECHANISM

Application filed February 13, 1928. Serial No. 254,090.

My invention relates to a new and useful improvement in an information display mechanism adapted for use for displaying advertising announcements, etc. It is particularly adapted for use on public conveyances, such as street cars, busses, trains and the like. It is also adapted for use in such buildings as depots, etc., for the purposes of displaying information which will advise 10 travelers as to the time of departure of trains, etc.

It is an object of the present invention to provide a mechanism of this class having a traveling flexible display member which may 15 be utilized to display matter on both sides.

It is another object of the invention to provide a mechanism for effecting the traveling of the flexible display member so that both sides thereof will be alternately exposed to 20 the exterior to display the advertising or written matter appearing thereon.

It is another object of the present invention to provide in a display mechanism of this class, a mechanism for operating the 25 same so as to move the flexible member a predetermined amount at each operation.

It is another object of the invention to provide a mechanism which will effect a movement of the device bodily.

30 Other objects will appear hereinafter.

The invention consists in the combination and arrangement of parts hereinafter described and claimed.

The invention will be best understood from 35 a reference to the accompanying drawings which form a part of this specification and in which,

Fig. 1 is a perspective view of the invention.

Fig. 2 is a central vertical sectional view 40 of the invention.

Fig. 3 is a sectional view taken on line 3—3 of Fig. 2.

Fig. 4 is a sectional view taken on line 45 4—4 of Fig. 2.

Fig. 5 is a fragmentary side elevational view of a part of the mechanism in the invention.

Fig. 6 is a fragmentary sectional view 50 taken on line 6—6 of Fig. 3.

Fig. 7 is a diagrammatic view illustrating the wiring of the invention.

Fig. 8 is a front elevational view of a modified form with parts broken away.

Fig. 9 is a sectional view taken on line 9—9 55 of Fig. 8.

Fig. 10 is a sectional view taken on line 10—10 of Fig. 8.

Fig. 11 is a diagrammatic view illustrating the wiring used in the modified form. 60

The invention comprises a housing formed from an upper section 15 which is secured to a suitable support 16 such as the roof of the vehicle by means of bolts 17. A cable 18 projects into a plug socket 19 which cooperates with the plug socket section 20 leading from which is the cable 21, a swivel, not shown, being interposed in the cable. Projecting inwardly from the upper section 15 is a flange 22 to afford a rest and guide for a thrust bearing comprising the rings 24 and 25. A flange 26 is formed on the conical member 27. Fixedly mounted on this member 27 at its lower end is a gear 28, the cable 21 being projected through the hub of the gear 28. The flange 26 is secured to the casting section 15 as shown in Fig. 2. The gear 28 meshes with a gear 29 fixedly mounted on the shaft 30 and rotated by the worm wheel 31 which meshes with the worm 32 which is fixedly mounted on the shaft 33 of the motor 34. The wire 21 connects to the motor 34 and serves to supply the necessary electrical energy. Slidably mounted on the portion 37 of the motor shaft which projects to the right 70 thereof is a friction disc 35 adapted to be moved into engagement with the disc 36, this disc 35 rotating with the shaft 37. When brought into engagement with the disc 36 this disc will be set into rotation and cause to 75 rotate the gear 38 which is secured thereto and projects from one face thereof. This gear 38 meshes with the gear 39 which carries on its face a gear 40 meshing with a gear 41 fixedly mounted upon the shaft 42 which is journalled in suitable bearings 43 and 44. A beveled gear 45 is fixedly mounted on the shaft 42 at one side of the medial line and a beveled gear 46 is fixedly mounted on the shaft 42 at the opposite side of the medial 80

line. This shaft 42 is axially movable and as shown in Fig. 3, the gear 40 is sufficiently wide to permit the axial movement of the gear 42 sufficiently to bring the gear 46 into mesh with the gear 49, and the gear 45 out of mesh with the gear 47, while at the same time, the gear 41 remains in mesh with the gear 40. The gear 47 is mounted on a spool 48 and the gear 49 is mounted on a spool 50 so that when the gear 47 rotates, the spool 48 will rotate, and, when the gear 49 rotates, the spool 50 will rotate. A flexible member 60 is adapted for winding on the spools 48 and 50 this flexible member passing around idlers or rollers 61 which are mounted on the inner casing 62. Projecting upwardly from this inner casing are arcuate bearing members 63 and 64. The roller section of the housing comprises a base 65 and a transparent wall 67, this roller section being fastened to the upper section by the clasp 66 and hingedly connected as at 66' so that it may be swung to the position shown in dotted lines in Fig. 1.

A magnetic coil 68 is used to effect the movement of the disc 35. The core 69 of the coil is embraced by a spring 70 and connected at one end to a pivotally mounted yoke 71. An arm 73 is fixedly mounted on the downwardly turned end 74 of the rod 69 and provided at opposite ends with rollers 75 and 75'. When the flexible member 60 is used for displaying stations or stops of a public vehicle, the flexible member will be provided with a plurality of slots 72 at pre-determined intervals depending upon the route which the vehicle is travelling. Wires 76 and 77 serve to connect the magnetic coil 68 to a source of electrical energy, the wire 77 passing through a switch 77' which may be normally retained in open position and closed when the conductor of the vehicle signals the starting of the vehicle. Wires 79 and 80 project from the cable 21 and connect to the motor 34 to supply it with the proper electrical energy, the wire 79 passing through a switch 81 which is normally closed.

In operation the motor 34 is continuously driven since the switch 81 is normally closed. This will effect a continuous rotation of the gear 29 which will cause the mechanism embodying the casing 62 and the spools and rotating mechanism to revolve about the gear 28 as a center so that the flexible member 60, which is exposed through the transparent wall 67 may be visible from different points.

It will be noted that this flexible member 60 is so wound that when passing around the member 64, one of the sides is exposed to the exterior and when passing around the member 63, the other side is exposed to the exterior as clearly appears from Fig. 4. The direction of rotation of the spools will depend upon whether the gears 45 and 47 are in mesh or whether the gears 46 and 49 are in mesh which may be regulated by axial movement of the shaft 42. When it is desired to rotate

the spool so as to expose a different section of the flexible member 60, the conductor or operator would close the switch 77, thus energizing the coil 76 so as to move the core or rod 69 axially against the tension of the spring 70 and thus rock the yoke 71 to move the disc 35 into frictional engagement with the disc 36. This would set the spools into rotation and the roller 75' would be in engagement with the flexible member 60 which would be drawn taut. Upon the closing of the switch 77', which may be of a spring-held type, the magnet 68 would be de-energized but the engagement of the roller 75' with the taut flexible member 60 would hold the rod or core 69 against the tension of the spring embracing it, in the position to which it was moved by the magnetic coil 68. Thus the discs 35 and 36 would remain in frictional engagement and a rotation of the spools would continue until a succeeding slot 72, which would be in alignment with the roller 75', and come into registration with the roller 75' upon which the rollers, engaging the slot, would permit the spring 70 to move the rod or core 69 in the opposite direction so as to disengage the disc 35 from the disc 36. By closing the switch 77', the operator may control the rotation of the spools and thus determine the matter to be displayed by the flexible member so that when the device is used for indicating stations or stops, the time of departure of trains, etc. the proper display may be had at all times.

In the modified form shown in Figs. 8 to 11, I have provided a casing 82 having slots 83 and 84 formed therein, each provided with a transparent closure 85 and 86 respectively. Spools 87 and 88 are mounted in this casing, and, wound upon these spools is a flexible member 89 on which the display matter may be printed or carried, this display matter riding in front of a guide 90 which is positioned in spaced relation to the transparent closures 85 and 86. Beveled gears 91 and 92 are fixedly mounted upon the shaft 93 and adapted to mesh with the beveled gears 95 and 94 respectively in the manner already described for the beveled gears 45 and 46. A motor 96 carries on its shaft a gear 97 meshing with a gear 98 which is fixedly mounted upon the shaft 93. Formed in the edge of the flexible strip 89 at spaced intervals, are notches 99 in which is adapted to engage the roller 101 carried by the rockably mounted arm 102. A magnet 103 is connected by the wires 104 and 105 to a suitable source of electrical energy, a switch 106 being interposed in the wire 105. When the magnet 103 is energized, the arm 102 will be rocked to bring the metallic contact 106', which is mounted on the arm 102 and insulated therefrom, into engagement with the contacts 107 and 108 which are interposed in the wire 109 which leads to the motor 96.

This motor 96 is also connected by the wire 111 to a suitable source of electrical energy. The operation is such that when the switch 106 is closed, the arm 102 will be rocked so as to close the circuit to the motor 96 and thus set the spools into rotation so that the flexible member 89 is brought to a position where the roller 101 is not in registration with any notch 99. When the roller 101 is 5 riding on the edge of the flexible member 89, the contact 106 will be in engagement with the contacts 107 and 108, thus maintaining the circuit to the motor 96 closed until a succeeding notch is moved into registration with the roller 101, in which event, the roller will engage in the notch, the circuit to the motor will be opened, and the winding on the spool will cease.

In this manner, I have provided a simple 20 and effective means for displaying advertising matter and other information and have accomplished the results herein mentioned.

While I have illustrated and described the preferred form of my invention, I do not 25 wish to limit myself to the precise details of structure shown but desire to avail myself of such variations and modifications as come within the scope of the appended claims.

Having thus described my invention, what 30 I claim as new and desire to secure by Letters Patent is:

1. A display mechanism of the class described comprising: a housing; a flexible display member in said housing, a portion of the 35 same being visible at the same time from opposite sides of said housing; and means for effecting the traveling of said flexible member in said housing to display one side of said flexible member through one side of said 40 housing and the other side of said flexible member through the other side of said housing; and means for effecting a rotation of said housing.

2. A display mechanism of the class described comprising: a housing; a flexible display member in said housing, a portion of the same being visible at the same time from opposite sides of said housing; and means for effecting the traveling of said flexible member in said housing to display one side of said flexible member through one side of said housing and the other side of said flexible member through the other side of said housing; and means for effecting a rotation of 55 said housing simultaneously with the traveling of said flexible member.

3. A display mechanism of the class described comprising: a housing having a portion of the side walls transparent; a supporting member rotatably mounted in said housing; winding means carried by said supporting member; a flexible display member wound on said winding means; guide members on said supporting member for guiding said flexible member while being wound; en-

gagement members on said supporting member for engaging said flexible member, the arrangement of said winding means, said guide means and said engagement members being such that at one side of said supporting 70 member from the exterior thereof, one side of said display member is visible and from the opposite side thereof the other side of said display member is visible.

4. A display mechanism of the class described comprising: a housing having a portion of the side walls transparent; a supporting member rotatably mounted in said housing; winding means carried by said supporting member, a flexible display member wound on said winding means; guide members on said supporting member for guiding said flexible member while being wound; engagement members on said supporting member for engaging said flexible member, the arrangement of said winding means, said guide means and said engagement members being such that at one side of said supporting member from the exterior thereof, one side of said display member is visible and from 80 the opposite side thereof, the other side of said display member is visible; and means for rotating said supporting member in said housing.

In testimony whereof I sign this specification.

ERWIN EICHENBERGER.
